G. L. WHEELOCK

APPARATUS FOR HANDLING ARTICLES TO BE TREATED WITH A LIQUID

Filed Dec. 23. 1921

UNITED STATES PATENT OFFICE.

GEORGE L. WHEELOCK, OF NEW YORK, N. Y.

APPARATUS FOR HANDLING ARTICLES TO BE TREATED WITH A LIQUID.

Application filed December 23, 1921. Serial No. 524,444.

This invention relates to apparatus for treating articles, as, for instance, in dish-washing, and one of the objects of the invention is to provide means for lifting the articles out of the liquid, or from the water, if the apparatus is used in dish-washing. Specifically, when the apparatus is used in dish-washing, an object is to provide a dish-pan with means for supporting a dish-holder thereon in such a way that the dish-holder is lowered into the pan when the dishes or the like are being washed, such means being adapted for enabling the dish-holder to be raised and to be held raised relatively to the pan when the dishes are to be wiped. Another object is to provide a simple, practical and efficient apparatus for washing dishes or the like; for dyeing, as by dipping the article supported on the support therefor into the dye liquid; and for any other purpose for which apparatuses of the kind may be used.

These being among the objects of the present invention, the same consists of certain features of construction and combinations of parts to be hereinafter described, and then claimed with reference to the accompanying drawings illustrating one embodiment of the invention, and in which—

Fig. 1 is a sectional elevation of the apparatus in full lines, the support or holder being submerged, and the dotted lines showing the elevated position of the holder;

Fig. 2 is a perspective view of the holder or cage;

Fig. 3 is a perspective view of the liquid receptacle or pan, with the improved means applied for enabling the adjustment of the holder relatively to the receptacle;

Fig. 4 is a sectional detail view, showing how one of the supporting feet or lugs is attached to the receptacle;

Fig. 5 is a plan of said detail;

Fig. 6 is an elevation of a supporting member such as shown in said views, said member being shown as flat;

Fig. 7 is a sectional detail of modified means for securing the said member;

Fig. 8 is a sectional detail of another modification thereof; and

Fig. 9 is a perspective view of a modified form of supporting member.

Referring to the drawing, the liquid receptacle 10 may be of any suitable shape,

open at the top, and adapted to contain a suitable liquid. In the case of a dish-washer, the receptacle would be preferably in the form of a dishpan composed of suitable sheet metal. Adapted to be positioned within the liquid receptacle 10 is a holder 11 for the things or articles to be treated with the liquid, and preferably, the said holder is in the form of a wire cage or basket, the meshes being fairly large so as to allow the liquid in the receptacle to freely run out of the cage when the same is raised above the liquid in the receptacle as in dotted lines, Fig. 1. When the apparatus is to be used as a dish-washer the holder or cage 11 should be strongly constructed.

The holder or cage 11 is preferably provided with means for supporting it from the upper edge of the receptacle or pan, to which end there may be placed at diametrically opposite sides of the holder or cage two hangers 12, 13. Each hanger 12, 13 is preferably composed of suitable heavy wire so as to support the weight of the articles or things in the holder or cage from the top of the receptacle, and for additional purposes hereafter referred to. Each hanger 12, 13 is preferably formed with spreading or divergent arms 14, which are secured at the bottom edge, or bottom wire, of the holder or cage by means of eyes 15 formed in the wire. Or the arms may be secured to the side wall of the holder or cage by soldering or any other desired manner, although the securing of the hangers by means of the eyes 15 is preferred, for, if an annular heavy wire forms the bottom edge of the holder or cage, the eyes 15 may be engaged loosely with such wire so that the hangers may have a certain degree of swinging motion. The upper ends of the hangers 12, 13 are each formed with a hook 16, and each hook is preferably curved, so that something in the nature of a recess is formed at the underside of each hook.

The holder or cage 11 is preferably large enough to about half fill the receptacle 10, but the size will depend upon the purpose to which the apparatus is put. When the holder or cage 11 and the receptacle 10 are of approximately the relative proportions illustrated, it will be seen that the hangers 12, 13 extend upwardly and diverge more or less from the holder 11. Preferably, the

proportions of the liquid receptacle and holder or cage are such that when the hooks 16 are resting upon the upper edge or rim of the receptacle or pan 10, the bottom of the holder will just clear the bottom of the receptacle and not rest thereon, although, if desired, the holder or cage 11 may rest upon the bottom of the pan, and when the holder is so lowered the hooks 16 may be disengaged from the edge or rim of the receptacle.

At opposite sides of the receptacle or pan 10 there are two supporting members 17, 18, and while these members are preferably made removable from the receptacle they may be made so as to form a permanent part thereof. The construction of each of the supporting members 17, 18 is preferably identical, and when made removable each may be constructed as follows: Supporting member 17, for example, is provided with an inclined edge 19 which constitutes an inclined-way, at the upper edge of the said member when the latter is applied to the receptacle. Each supporting member 17, 18 is provided with feet or lugs 20, which may be soldered, welded, riveted, or otherwise firmly attached to the supporting member. Two of these feet or lugs are shown, but the number may of course be varied, and the preferred details of these lugs and adjacent parts are fully disclosed in Figs. 4 and 5. Each foot or lug 20 is long enough so that it may rest upon the upper rim of the receptacle, and it is extended sufficiently so as to project beyond such rim, it being preferably formed with the shoulder 20* at about the point the outer edge of the rim would ordinarily be. A keeper 21 is secured by a pivot 22 to the outer end of each lug 20 in such a position that when the lugs or feet are resting upon the rim of the receptacle, each keeper may be swung around underneath the rim of the receptacle,—the keeper having its end upturned so as to engage behind the outer edge or bead on the rim of the receptacle. In some such way the inclined supporting members may be secured to the receptacle, and when the attaching means are as just described there should preferably be some slight spring in the parts so that the upturned end or toe of the keeper can snap behind the bead or edge of the receptacle's rim. Preferably, each supporting member 17, 18 is made of such vertical width that the lower edge of the same will extend below the top edge of the receptacle in the form of a skirt or underhang, such as 23. When the supporting members are applied to the receptacle the underhangs 23 thereof will be at the inside of the receptacle, while the attaching means will engage the outer portion of the rim thereof.

The supporting members are so applied in such position on the receptacle that their inclined-ways 19 will incline or slant in

opposite or reverse directions, and when properly attached to the receptacle they preferably will be at opposite sides thereof, and the upper edge or rim of the receptacle will merge, as it were, into the inclined-ways 70 19. The hooks 16 of the hangers resting upon the upper edge of the receptacle may be caused to travel upon the inclined-ways 19 which are curved lengthwise in segments of a circle which have the vertical axis of 75 the receptacle as their approximate center, by imparting a turn or twist to the holder or cage and its hangers, the hooks 16 engaging with the inclined-ways and the entire cage, contents and hangers being elevated to the upper ends of the inclined supporting members. The said supporting members are preferably recessed at the upper ends of the inclined, as at 24, to provide shoulders at each end of each recess, and into these recesses the hooks 16 may be engaged and the holder or cage retained against accidental dislodgment.

Inasmuch as the hangers 12, 12, are preferably hinged to the holder 11 and preferably have recesses provided by the undersides of the hooks 16, 16, the hangers may be moved to cause the initial engagement of the lower ends of the inclined ways 19, 19, with the recesses, without requiring the lifting of the holder 11, and it then becomes an easy matter to raise the holder by giving it the necessary twist until the hooks engage in the recesses 24. Because of these preferred features the hangers will be self-adjusting to any irregularities in the inclined ways or to any non-concentricity of the same with the vertical axis of the receptacle 10, although generally the inclined ways will be set to curves which are longitudinal thereof and are substantially concentric with the vertical axis of the receptacle 10.

When the apparatus is in use for washing dishes of the like, the holder or cage is lowered into the receptacle, and the apparatus may be placed under water faucets so as to allow the water to run into it on the dishes therein. If desired, a wire soap-holder of the type such as is commonly employed may be pivoted to one of the inclined supporting members so that it may be swung into or underneath the water faucet to allow the water to dissolve some of the soap, and when finished with the soap-holder it may be swung back out of the way. When the washing of the dishes is finished, the person making use of the apparatus may take hold of the holder or the hangers and turn the holder or cage and the contents sufficiently to elevate the contents out of the water and to engage the hooks 16 with the recesses 24 in the supporting members. This will allow the water to drain from the dishes or the like, and they can then be wiped. As before intimated, the apparatus may of course be

used for other purposes, and the operation thereof may be reversed. Articles or things may be placed in the holder or cage when the latter is in raised position, and it may then be lowered into any liquid that may be contained in the receptacle, to be raised later from the liquid, if desired.

As most dishpans are made flaring it may be preferred to use the means illustrated in Fig. 7 for securing the inclined supporting members to the pan, as such means may hold better than the means illustrated in Fig. 4. In Fig. 7 lugs such as 25 are rigidly secured to the inclined supporting members, and each lug is adapted to rest upon the rim of the pan, and has a shoulder 26, which may engage over the outer edge of the rim so as to constitute one member of a clamp. The other member of the clamp may be furnished by a set-screw 27, which is threaded into the lower part of the supporting member so that it may be caused to bear upon the inner surface of the pan.

In Fig. 8 there is shown a modification in which the supporting members, such as 17, 18, are not provided with a skirt or underhang portion, and to which are attached one or more lugs 30, preferably of resilient sheet metal, the lug or lugs being formed with a humped clip portion 31, so that the parts 30, 31 constitute a spring-clip which may be engaged over the rim of the liquid receptacle or dishpan, with the humped portion engaged behind the bead of the rim. The action of the lug resting upon the rim of the receptacle, supplemented by the spring action of the means engaging the rim, will hold the supporting member in upright position, whether vertical or inclined.

Each of the supporting members may be composed of sheet metal, which may be of a springy nature so that they will be flat, as in Fig. 6, when not in use, and may be hung up in some convenient position through the medium of holes therein to receive a supporting nail. If of springy metal, they may then be bent to the curvature of the edge of the receptacle to which they are to be applied, and the spring-set in the supporting members may then assist in retaining them upon the receptacle. In this case the curvature of the supporting members may be altered so as to adapt them to receptacles or pans of varying diameters.

It may be found more desirable to make the supporting members of wire, so that the entire apparatus, with the exception of the receptacle, would be composed of wire. In Fig. 9 a desirable form of wire supporting member is illustrated. The principle illustrated is similar to the illustration in Fig. 8. In Fig. 9 the supporting member is shown as having an intermediate portion 32 of such incline as to form an inclined-way, while at the top of the inclined-way, the wire is bent

downwardly so as to form a recess 33, into which the hook on a hanger of the article holder may be engaged. At the lower end of the inclined portion the wire supporting member is formed with a spring-clip 34, while the other end of the supporting member is formed with a downturned portion 35, the lower end of which is formed into the spring-clip 36, the two clips being presented in the same direction. By means of the spring-clips referred to, the supporting member may be engaged with the rim of the receptacle and held in upstanding position.

Obviously, the invention is susceptible to more or less modification, which would still be within the scope of the appended claims.

What I claim as new is:

1. Apparatus of the class described comprising, in combination, a receptacle for a liquid, a holder for the things to be treated, and located in the receptacle, holder-supporting means having upper recesses in which the holder may be engaged, and guiding means extending from and above the receptacle up to said recesses and through which, by a partial turning movement of the holder, said holder may be caused to be elevated relatively to the receptacle and to be engaged with said recesses at will.

2. Apparatus of the class described, comprising a receptacle for a liquid, oppositely inclined guide-ways extending above the upper edge of the receptacle and curving lengthwise in curves having the vertical axis of the receptacle as their approximate center, hangers adapted to be engaged with said edge and to be laterally shifted from said edge directly on to said ways, means at the upper ends of said ways for interrupting the shifting of said hangers on the ways, and a holder for things to be treated carried by said hangers.

3. Apparatus of the class described, comprising a receptacle for a liquid, inclined guide-ways above the upper edge of the receptacle, means lateral of the ways for detachably connecting them with said receptacle to incline oppositely, said ways being formed in separate segments of a circle which extend lengthwise in curves having the vertical axis of the receptacle as their approximate center, and a holder for things to be treated movable on said ways.

4. A liquid receptacle provided with means for elevating a holder thereon, said means comprising oppositely inclined guide-ways at the upper edge of the receptacle curving lengthwise in curves having the vertical axis of said receptacle as their approximate center, and said ways being recessed at their upper ends.

5. Apparatus of the class described, comprising the combination of a basket, and wire hangers having arms which are pivoted to the basket, each of said hangers being

4
formed with an outwardly extending hook between its arms, the hook providing an under recess, a receptacle, the upper edge of which may engage in said recesses when the basket is lowered in the receptacle, shoulders on the upper edge of said receptacle located to one side of each point of the edge

engagement of said hooks for engagement with the hooks when the basket is raised, and inclined guide-ways extending between 10 the said engaging upper edge and said shoulders.

GEO. L. WHEELOCK.
